UNITED STATES PATENT OFFICE.

GUSTAV BEHRNS AND GUSTAV UNRUH, OF LUBECK, GERMANY.

ELEVATOR.

SPECIFICATION forming part of Letters Patent No. 248,985, dated November 1, 1881.

Application filed July 5, 1881. (No model.)

To all whom it may concern:

Be it known that we, GUSTAV BEHRNS and GUSTAV UNRUH, citizens of and residing in the free city of Lubeck, Empire of Germany, 5 have invented a new and useful Improvement in Elevators and Hoisting Apparatus, which improvement is fully set forth in the following specification and accompanying drawings, in which—

10 Figure 1 is a side elevation of the elevator and hoisting apparatus embodying our invention, the hull of the vessel whose contents are to be discharged being shown in vertical section. Fig. 2 is a top or plan view thereof. Fig. 15 3 is a side view, enlarged, partly sectional, of a detached portion thereof. Fig. 4 is a vertical section of Fig. 3. Fig. 5 is a top view of Fig. 3. Fig. 6 is a vertical section of the elevator-buckets employed in the present case; 20 but other forms may be adopted.

Similar letters of reference indicate corresponding parts in the several figures.

Our invention consists of a frame formed of a series of bars jointed together after the manner of lazy-tongs, a number of pulleys, and an endless bucket-conveying band, whereby the frame may be adjusted relatively to the locality from whence the load is to be elevated or discharged, said frame then serving as a rigid 25 30 frame to sustain the endless bucket-conveying band as the buckets are filled, elevated, discharged, and returned.

It also consists of a gravitating pulley, in combination with an endless bucket-conveying 35 40 band and an extensible depending frame provided with pulleys, over which said band passes, said gravitating pulley causing said band to automatically adjust itself to the contracting and expanding of said frame.

45 It also consists of a depending extensible lazy-tongs frame provided with a chain and pulleys for shortening and lengthening said frame, and with other pulleys for the passage of an endless band, in combination with said band, the buckets carried thereon, and the crane or frame of the device.

It also consists of a depending lazy-tongs frame, in combination with a crane or frame and an intermediate swinging frame, which 50 forms a double joint for the lazy-tongs frame,

whereby provision is made for the lateral adjustment of the latter.

Referring to the drawings, A represents the float or support of the elevator, and Z the vessel to be discharged. 55

B represents a crane, which is fitted in a step, c, on the support A as a vertical axis, so that it may be readily swung around relatively to the position of the vessel Z.

E represents the engine operating the belt- 60 ing or gearing of the elevating mechanism, and F the steam-boiler thereof, both properly placed on the float or support A.

To the outer end of the horizontal limb of the top of the crane B is pivoted, by means of 65 bolts g, a swinging frame, y, from which depends a jointed frame, H, formed of bars h, pivoted, as at i k, after the manner of lazy-tongs, said swinging frame y also supporting a shaft, on which are keyed or otherwise secured pulleys n, as most clearly seen in Fig. 5. The bottom of the lazy-tongs frame also carries similar pulleys, n², and similar pulleys are mounted on the horizontal and vertical limbs of the crane, for the guidance and support of the endless belts or conveyers s of the buckets t, which belts pass around the pulleys n, n², o, and g. The pulleys q have their bearings fitted freely in vertical guides r r on the upright limb of the crane, whereby said pulleys by their gravity 70 75 serve to maintain the tension of the endless belts s.

Attached to the central pivot of the lowest bars of the lazy-tongs frame are chains l, which pass around pulleys m on the crane, and are 85 wound on a drum, m', conveniently accessible. The power of the engine or motor is communicated to the pulley q by the belt u, and movement is thus imparted to the belts s, which, carrying the buckets t, move the latter into the 90 load and then elevate them. (See the direction of the arrow, Fig. 3.) When the loaded buckets reach the pulleys o their contents are discharged into the spout p, and thence directed to other parts of the elevator proper. 95

It will be seen that the lazy-tongs may be raised and lowered or folded and unfolded, the frame H thus being adapted to be adjusted relatively to varying depths of holds of ships and other localities to be discharged of their 100

contents. When the frame is to be shortened the chain l is wound on the drum m' . This folds the bars of the lazy-tongs, and the slack of the bucket conveyer or bands s is immediately taken up by the gravitating-pulley q , around which said bands are passed, as has been stated. When the frame H is to be lengthened, in order to penetrate greater depths, the chain is unwound from the drum m' and the bars of said frame H unfold, the frame lowers, and the weight of the conveyer and bucket raises the pulley q , thus keeping said conveyer or belts s at the proper tension.

Provision is made for the slack of the belt u , which communicates the power of the engine or motor to the gravitating pulley q . The folding and unfolding of the bars of the frame H also facilitate the introduction of the said frame into and from the ship or other locality. The top frame, y , suspended from the bolts or axis g , permits the lazy-tongs frame H to be swung or moved laterally, and the pivotal connection of said frame H with the frame y allows the frame H to be moved or swung inwardly and outwardly as a double joint, and thus the load may be readily reached when in places otherwise inconvenient of access.

The bottom of the frame H is properly guarded for preventing injury, &c., to the pulleys n by bars, &c., at said bottom.

The buckets are scoop-shaped and connected at their sides and rear ends to the belts s , whereby, after they have entered the hold, &c., and passed into the grain, &c., and are filled with the same, they assume an upright position until they reach the top limb of the crane, and then a horizontal position until they reach the pulley o , where they are overturned and discharged, after which they pass around the pulleys q , and so return to the ship, &c.

If desired, the crane may be mounted on a lighter, to receive a load, or its load be discharged and directed therefrom to another locality, and the crane may be placed on rails for shifting and adjusting purposes.

Having thus described our invention, what we claim as new, and desire to secure by Letters Patent, is—

1. An elevator having an extensible frame formed of jointed bars after the manner of 50 lazy-tongs, pulleys, and an endless bucket-conveying band, substantially as set forth.

2. A gravitating pulley, in combination with an endless bucket-conveying band and an extensible depending frame provided with pulleys, over which said band passes, said gravitating pulley causing said band to automatically adjust itself to the contracting and expanding of said frame.

3. A depending extensible frame formed of 60 jointed bars after the manner of lazy-tongs, provided with a chain and pulleys for shortening and lengthening said frame, and with other pulleys for the passage of an endless bucket-conveying band, in combination with said 65 band, the buckets carried thereon, and the crane or frame of the device.

4. The lazy-tongs frame, in combination with the crane and a swinging frame, forming a universal joint for the lazy-tongs frame, substantially as and for the purpose set forth.

In testimony whereof we have signed our names to this specification in the presence of two subscribing witnesses.

GUSTAV BEHRNS.
GUSTAV UNRUH.
